UNITED STATES PATENT OFFICE.

ALBERT DECATUR BARR, OF McHUE, ARKANSAS.

MEDICAMENT AND PROCESS OF PRODUCING THE SAME.

1,235,278.

Specification of Letters Patent. Patented July 31, 1917.

No Drawing.

Application filed October 1, 1913. Serial No. 792,741.

To all whom it may concern:

Be it known that I, ALBERT DECATUR BARR, a citizen of the United States, residing at McHue, county of Independence, State of Arkansas, have invented new and useful Improvements in Medicaments and Processes of Producing the Same, of which the following is a specification.

This invention relates to medicaments and processes of producing the same; and it comprises a stimulating, antipyretic, crystalline salt containing as proximate elements an antipyretic derivative of the anilin group of the anilid type, and a vegetable alkaloid of appropriate therapeutic properties; and it also comprises a process of producing such medicament by the treatment of an anilid derivative with an organic acid and the subsequent union of an alkaloid to the body so treated, all as more fully hereinafter set forth and as claimed.

In my Patent No. 966,786 of August 19th, 1910, I have described a stimulating antipyretic, crystalline saline body and method 25 of producing it and referred to the value of the same. My present invention relates to a similar saline body having similar physiological effects.

I have discovered that upon treating acetanilid with the right amount of an organic acid, such as citric acid, under certain conditions, the acid may be made to enter into combination with the acetanilid and that this combination can be rendered stable by 30 the addition of an alkaloid, specifically caffeine, which enters into chemical combination therewith, with the result that there is obtained a definite chemical combination having antipyretic value without concomitant 35 depressing action on the heart.

The process will be readily understood from the following:

To 6598.62 grains of citric acid ($H_3C_6H_5O_7$) I add about a pint of water and heat to the 45 boiling point. To this solution is added 4458.53 grains of acetanilid ($C_6H_5NH.C_2H_3O$) or its equivalent and the compound thus formed is boiled for about thirty minutes.

To this is added 7000 grains of caffeine ($C_8H_{10}N_4O_2$) and the mass is boiled for two and one-half hours, care being taken to add, from time to time, the water lost by evaporation.

At the end of this time the solution is placed over a water bath and evaporated

until the compound weighs about 18057.15 grains, at which time it has become a true chemical compound of thick, syrupy consistency. It is then set aside in a cool place, 60 free from dust, and allowed to crystallize for about from three to six weeks. The result is a true chemical combination containing acetanilid, citric acid and caffeine molecules ($C_6H_5NHC_2H_3O$, $H_3C_6H_5O_7$, $C_8H_{10}N_4O_2$) in the proportions of ten parts acetanilid, 14.81 parts of citric acid and 15.7 parts of caffeine. On analysis it yields 24.6852 per cent. acetanilid; 36.5607 per cent. citric acid; and 38.7754 per cent. caffeine. It dissolves in about its own weight of water and is slightly hygroscopic during the warm weather. The medicinal adult dose is from five to twenty-five grains and it is advantageous in all pathological conditions where 75 there is a rise of temperature above 100.3.

In the foregoing, I have mentioned acetanilid as the antipyretic salt. For it may be substituted one of the other antipyretic derivatives of the anilin group containing 80 the acetic acid molecule without departing from the spirit and scope of my invention. So, too, other elements than caffeine may be employed where the citric acid is used in combination, but I prefer caffeine in this 85 particular embodiment of the invention, as it gives a better balance between the heart-depressing and heart-stimulating properties of the final product.

What I claim is:

1. The process of making a stimulating antipyretic comprising mixing acetanilid and an organic acid in solution, heating the product formed, adding a vegetable alkaloid, evaporating the solution and allowing 95 it to crystallize.

2. The process of manufacturing a stimulating antipyretic which comprises mixing acetanilid and citric acid in solution, heating the same, adding caffeine and heating the 100 compound thus formed, and evaporating and crystallizing the resultant product.

3. As a new product, a stimulating antipyretic, saline substance containing groups derived from citric acid, acetanilid and caffeine in substantially the following proportions: acetanilid, 24.68 per cent.; citric acid, 36.56 per cent.; caffeine, 38.74 per cent., said substance being slightly hygroscopic during warm weather and being soluble in about its 105 own weight of water.

4. The process of making a stimulating

2
antipyretic composition which comprises mixing acetanilid and citric acid together in solution, heating the mixture, adding an alkaloid to produce a chemical compound 5 of the three, and evaporating and crystallizing the resultant product.

5. The process of making a stimulating antipyretic composition which comprises mixing a solution of citric acid and an anti- 10 pyretic derivative of the anilin group containing the acetyl radical, heating the mixture, adding a vegetable alkaloid, heating the compound thus formed, and evaporating and crystallizing the resultant product.

15 6. The process of making a stimulating antipyretic composition which comprises mixing a solution of an organic acid and an antipyretic derivative of the anilin group containing the acetyl radical, heating the 20 mixture, adding a vegetable alkaloid, heating the compound thus formed, and evap-

orating and crystallizing the resultant product.

7. As a new product, a stimulating anti- 25 pyretic saline substance containing a chemical combination of molecular proportions of acetanilid, citric acid and caffeine.

8. As a new product, a stimulating anti- 30 pyretic saline substance containing an organic acid, an antipyretic derivative of the anilin group containing the acetyl radical, and a vegetable alkaloid; crystalline in form; and having the property of decomposing without melting when heated.

In testimony whereof, I have hereunto set 35 my hand this 30th day of September, 1913, in the presence of subscribing witnesses.

ALBERT DECATUR BARR.
